DESIGN FOR A BROOCH PIN

Florence N. Lewis, New York, N. Y.

Application March 15, 1941, Serial No. 99,624

Term of patent 7 years

To all whom it may concern:

Be it known that I, Florence N. Lewis, a citizen of the United States, residing at New York, in the county of New York and State of New York, have invented a new, original, and ornamental Design for a Brooch Pin, of which the following is a specification, reference being had to the accompanying drawing, forming part thereof.

In the drawing

Fig. 1 is a front elevational view of a brooch pin, showing my new design;

Fig. 2 is a rear elevational view thereof.

Fig. 3 is a top plan view.

Fig. 4 is a sectional view along line 4—4 of Fig. 2.

I claim:

The ornamental design for a brooch pin, as shown.

FLORENCE N. LEWIS.
